UNITED STATES PATENT OFFICE.

ADOLPH M. SEEGER, OF TOLEDO, OHIO, ASSIGNOR TO THE SEEGER DEVICE COMPANY,
OF TOLEDO, OHIO, A CORPORATION OF OHIO.

PUSHING AND PULLING TOOL.

Application filed May 7, 1927. Serial No. 189,503.

This invention relates to tools, but more particularly to combined pushing and pulling tools.

Objects of this invention are to provide a new and improved tool which can be used as a pushing device or jack, and a pulling device by a simple change which can readily and conveniently be made; and to provide a tool of the above class having the novel features of construction and arrangement hereinafter described.

The invention is shown by way of illustration in the accompanying drawings, in which:

Fig. 1 is a side elevation of the tool; Fig. 2 is a transverse section on the line 2—2 of Fig. 1, and Fig. 3 is an enlarged fragmentary view with one of the plates removed to show the arrangement of the pawls and associated parts.

The illustrated embodiment of the invention comprises a tool having parallel bars 1 and 2 of bar metal. The bars 1 and 2 are spaced from each other, and formed on the outer edge of each bar is a series of rectangular teeth 3. The opposite ends of the bars 1 and 2 are closed by plates 4, which are secured together by rivets 5 extending through the bars.

Each pair of plates 4 is provided with registering openings 6 to permit the insertion of a threaded bolt 7 to hold a clevis 8 in place. The bolt 7 is screwed into the outer arm of the clevis 8, as will at once be apparent. By removing the bolt 7, the clevis 8 may be removed from one end and quickly and conveniently attached to the opposite end.

Slidable between the parallel bars 1 and 2 is an intermediate bar 9 having a clevis 10 detachably connected to the outer end thereof. The bar 9 may be inserted between the parallel bars 1 and 2 from either end thereof for purposes hereinafter described.

Disposed on opposite sides of and in transverse relation to the bars 1, 2 and 9 are plates 10', and detachably connected to the plates 10' by bolt and nut connections 11, is an operating handle 12. The outer ends of the plates 10' are held in spaced relation by a sleeve 13 through which extends a headed pin 14 held in place by a cotter pin 15. It will be apparent that the handle 12 and plates 10' form an operating lever, this lever being pivoted to the inner end portion of the intermediate bar 9 by a headed pin 16, which is held in place by a cotter pin 17.

Arranged on each side of the intermediate bar 9 and engageable with the rectangular teeth 3 on the bars 1 and 2 are pawls 18 which are pivoted on pins 19 intermediate the ends thereof. A spring 20 is provided for each pawl 18 for holding the inner end thereof in engagement with the teeth 3. The outer ends 21 of the pawls 18 extend in the same direction and are substantially parallel to each other so that an operator may grasp the outer end portions 21 of both pawls in a convenient manner to move the inner ends thereof away from the teeth to permit the bar 9 to be adjusted in either direction.

As the parts are arranged in the drawings, it will be seen that vertical swinging movement of the operating lever brings first one pawl and then the other into engagement with the respective teeth, thereby elevating the parallel bars 1 and 2 with respect to the intermediate bar 9. It is manifest that operation of the tool in this manner provides a jack to enable an object to be lifted or to exert a pushing force against an object engaged by the clevis 8 or upper end portion of the tool.

In order to adapt the tool for use in pulling an object toward a stationary point, the cotter pin 17 is first removed and pin 16 withdrawn. The intermediate bar 9 may then be withdrawn from the parallel bars 1 and 2. Thereafter the clevis 8 is disengaged to enable the intermediate bar 9 to be inserted between the parallel bars 1 and 2 from the opposite end of the tool. The clevis 8 may be attached to the lower end of the tool, and after again connecting the operating lever with the end portion of the intermediate bar 9 by the pin 16 and cotter pin 17, the tool is assembled for pulling. To and fro swinging movement of the operating lever gradually draws the outer end portion of the intermediate bar 9 inwardly toward the adjacent end of the parallel bars 1 and 2. The change of the parts so that the tool may be used for pushing or for pulling is accomplished quickly and in the simple manner above described.

This tool has been found to be of great utility in cable work and wire stretching. It is admirably adapted for the installation of telegraph and telephone lines, although it may be used for many and varied purposes.

While I have shown and described a con-

struction which is the best form known to me at the present time, it is to be understood that numerous changes in details of construction and arrangement may be effected without departing from the spirit of the invention, especially as defined in the appended claim.

What I claim as new and desire to secure by Letters Patent is:

- 10 A pushing and pulling tool including a pair of spaced bars each having teeth on the outer side edges of the bars, means connecting each of the ends of the bars so as to leave open space at each of the ends of the bars, an intermediate bar in the space between said
- 15 pair of bars having attaching means on one end and having its opposite end formed to

be selectively inserted in said open space at either end of the bars, a lever having pawls to engage the teeth on each of the said pair of bars, means to removably pivot the lever to the intermediate bar, and attaching means 20 removably engageable with either of said connecting means of the pair of bars whereby upon removal of the pivoting means and of said last named attaching means the intermediate bar may be inserted from either end 25 of the pair of bars so as to adapt the tool for pulling when inserted in one end of the pair of bars and for pushing when inserted in the opposite end of said pair of bars.

In testimony whereof I have hereunto signed my name to this specification.

ADOLPH M. SEEGER.
